UNITED STATES PATENT OFFICE.

ELMER NICE, OF PHILADELPHIA, PENNSYLVANIA.

CARBURETER.

1,084,954.

Specification of Letters Patent. Patented Jan. 20, 1914.

Application filed November 26, 1912. Serial No. 733,578.

To all whom it may concern:

Be it known that I, ELMER NICE, a citizen of the United States, residing at Philadelphia, in the county of Philadelphia and State of Pennsylvania, have invented certain new and useful Improvements in Carbureters, of which the following is a specification.

My invention relates to improvements in carbureters, the object of the invention being to provide an improved mechanism which automatically and simultaneously controls the proportion of liquid and air, and facilitates the commingling of the air and vapor, so that a good mixture is the result.

A further object is to provide a carbureter with a plurality of air passages directing the air into contact with the liquid or vapor, and provide a movable member which simultaneously controls the flow of air through the passages and also controls the feed of liquid fuel.

A further object is to provide a carbureter of this character in which there is no possibility of back fire reaching the liquid fuel.

A further object is to provide a carbureter of this character which will be of extremely simple inexpensive construction, strong and durable in use.

With these and other objects in view, the invention consists in certain novel features of construction and combinations and arrangements of parts as will be more fully hereinafter described and pointed out in the claims.

In the accompanying drawings: Figure 1 is a view in longitudinal section illustrating my improvements. Fig. 2 is a perspective view of one of the disks 15. Fig. 3 is a view in cross section on the line 3-3 of Fig. 1. Fig. 4 is a view in horizontal section on the line 4-4 of Fig. 1. Fig. 5 is a similar view in section on the line 5-5 of Fig. 1, and Fig. 6 is a fragmentary view in section on the line 6-6 of Fig. 4.

1 represents the cylindrical casing of my improved carbureter, having a bottom 2 secured to the lower end of the casing and a top 3 to the upper end of the casing. The top 3 is integral with an outlet tube 4 having an ordinary throttle valve 5 therein, and adapted to be connected to the intake of an internal combustion engine. A depending cylinder 6 is fixed to the top 3 in

any approved manner, is concentric with the wall of casing 1, and is provided at opposite sides with longitudinal slots 7 through which a bar 8 projects. This bar 8, at its ends, is secured to an annular piston 9, and between its ends is secured a rod 10.

The rod 10 is guided in its vertical movement by means of a transverse bar 11 secured in tube 4, and this upper portion of the rod is screw-threaded for the reception of nuts 12 located at opposite sides of bar 8, and securing the bar and rod together. A coiled spring 13 is preferably located around the rod between bars 11 and 8, and exerts a light downward pressure upon the piston 9. The bottom 2 has formed centrally on its upper face a circular boss 14 having its outer wall in line with the outer wall of cylinder 6, it being understood that the lower end of cylinder 6 terminates an appreciable distance above the boss 14.

Between the boss 14 and the lower end of the cylinder 6, a plurality of disks 15 are located. These disks are of an external diameter, the same as the external diameter of cylinder 6 and boss 14, so that the piston 9 is free to move vertically and is of an internal diameter just sufficient to snugly fit the cylinder 6, the disks 15, and the boss 14. While this piston may be variously constructed, it is preferably formed with a depending flange 16 which operates to cut off the spaces between the several disks 15. These disks 15 are spaced apart as indicated. That is to say, the lower disks are closer together than the upper disks, and the spaces between the disks gradually increase from the lowest disk to the highest disk.

While, of course, various means may be resorted to for spacing the disks, I preferably position blocks 32 between the disks, and then project bolts 33 through all of the blocks and through lugs 34 on cylinder 6, and screw the lower ends of these bolts into the boss 14. This construction is clearly illustrated in Fig. 6. Each disk has an open center, and around the open center, the disk is provided with a beveled annular flange 17, each successive disk in the series having a larger opening and a consequent larger flange. In other words, the smallest disk has the smallest opening, and flange, and each successive disk above has a relatively larger opening and flange, so that at the center these flanges present a general conical formation. The rod 10 is tapered at

its lower end forming a needle valve 18 which controls the flow of liquid fuel from a supply tube 19 projecting into the center of the boss 14. This supply tube 19 is externally screw-threaded to mesh with internal threads in a nut 20. The nut 20 has rotary mounting in a plate 21, secured to the bottom 2 by screws 22, and a hand wheel 23 is fixed to the nut 20, so that when the latter is turned, the tube 19 will be adjusted vertically to time the cut off of liquid fuel to exactly suit conditions. Casing 1 is provided at one side with an air inlet 24, and while this inlet at its outer end is circular to fit an ordinary pipe, it gradually changes in form to that of an ellipse as shown at 25, so as to give the maximum of air inlet space to the casing. In the top 3, a plurality of valves 26 normally close ports 27 in the top 20 of the casing, and the stems 29 of said valves are mounted to move in lugs 30 on tube 4, and are held in closed position by coiled springs 31. It is of course to be understood that the piston 9 fits the casing 1 as well as cylinder 6, but said piston at its outer edge is formed with a relatively small flange 35 as compared with the flange 16.

In Fig. 1 the parts are shown in partially open position, the liquid fuel being drawn through the pipe 19, and the air sucked through the space between the lower disks. As the suction increases, the piston will be drawn upwardly and at the same time will enlarge the liquid fuel outlet and also the air inlet. By reason of the construction and arrangement of disks, it will be seen that air will flow in all directions from the outside of the disks to the center thereof, and by reason of the flanges 17 this air will be directed upwardly in the direction of the movement of the gas. An increased suction, therefore, increases the amount of air over that of liquid fuel. In other words, as the suction increases, the relative proportion of air over liquid increases. This is due to the increased spaces between the several disks 15. As the suction diminishes, the piston will fall and gradually cut off the air and then the liquid. It will be noted that the air will be cut off before the liquid, and on the reverse movement the liquid supply will be opened slightly ahead of the air, so that the first mixture is rich and gradually becomes poorer in proportion to the suction. In case of back fire, the gases will escape through the ports 27, valves 26 opening to permit such escape and prevent any possibility of back fire reaching the liquid fuel. While I use the term "liquid fuel", I would have it understood that my carbureter is especially adapted for use with gasoline and similar highly volatile liquids such as commonly used in connection with internal combustion engines.

16 The several parts are capable of a wide

range of adjustment in accordance with the mixture desired, and various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A carbureter comprising a casing having a depending wall terminating short of the bottom of the casing and forming an annular piston chamber around the wall, means below the wall for directing air into the chamber formed in the interior thereof, a piston around the wall movable relative thereto, said piston adapted to control the flow of air below the lower end of the wall, and means connected to the piston controlling the flow of liquid to the space inclosed by the wall, substantially as described.

2. A carbureter comprising a casing having a depending wall terminating short of the bottom of the casing and forming an annular piston chamber around the wall, means below the wall for directing air into the chamber formed in the interior thereof, a piston around the wall movable relative thereto, said piston adapted to control the flow of air below the lower end of the wall, a liquid supply tube discharging liquid into the lower end of the casing, and a needle valve carried by the piston and controlling the outlet from said supply tube, substantially as described.

3. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, and a piston fitting the annular chamber and adapted to cut off the space between the disks, substantially as described.

4. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to cut off the space between the disks, said disks having central openings and inclined upwardly projecting flanges around said openings, substantially as described.

5. A carbureter comprising a cylindrical casing, a concentric cylinder in the casing forming an annular chamber between the cylinder and the wall of the casing, a plu-

rality of disks below the cylinder spaced apart and communicating with the casing, said casing having an air inlet, a piston fitting the annular chamber and adapted to 5 cut off the space between the disks, said disks having central openings and inclined upwardly projecting flanges around said openings, the lowermost disks closest together, and the disks above spaced from those below 10 by increasing amounts, the smallest spaces being between the lower disks and the largest spaces between the upper disks, substantially as described.

6. A carbureter comprising a cylindrical 15 casing, a concentric cylinder in the casing forming an annular chamber between the cylinder and the wall of the casing, a plurality of disks below the cylinder spaced apart and communicating with the casing, 20 said casing having an air inlet, a piston fitting the annular chamber and adapted to cut off the space between the disks, said disks having central openings and inclined upwardly projecting flanges around said 25 openings, the opening in the lowest disk being smallest and in the upper disk largest, and the openings in the disks between the upper and the lower disks varying in size in regular ratio, substantially as described.

30 7. A carbureter comprising a cylindrical casing, a concentric cylinder in the casing forming an annular chamber between the cylinder and the wall of the casing, a plurality of disks below the cylinder spaced 35 apart and communicating with the casing, said casing having an air inlet, a piston fitting the annular chamber and adapted to cut off the space between the disks, said disks having central openings and inclined upwardly projecting flanges around said 40 openings, the lowermost disks closest together, and the disks above spaced from those below by increasing amounts, the smallest spaces being between the lower disks and the largest 45 spaces between the upper disks, the opening in the lowest disk being smallest and in the upper disk largest, and the openings in the disks between the upper and the lower disks varying in size in regular ratio, substantially 50 as described.

8. A carbureter comprising a cylindrical 55 casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to 60 cut off the space between the disks, a liquid supply pipe communicating with the center of the lowermost disk, and a needle valve carried by the piston and controlling the outlet from said liquid supply pipe, substantially as described.

55 9. A carbureter comprising a cylindrical

casing, a concentric cylinder in the casing forming an annular chamber between the cylinder and the wall of the casing, a plurality of disks below the cylinder spaced apart and communicating with the casing, 70 said casing having an air inlet, a piston fitting the annular chamber and adapted to cut off the space between the disks, said disks having central openings and inclined upwardly projecting flanges around said openings, a liquid supply pipe communicating with the center of the lowermost disk, and a needle valve carried by the piston and controlling the outlet from said liquid supply pipe, substantially as described. 75

10. A carbureter comprising a cylindrical 80 casing, a concentric cylinder in the casing forming an annular chamber between the cylinder and the wall of the casing, a plurality of disks below the cylinder spaced apart and communicating with the casing, 85 said casing having an air inlet, a piston fitting the annular chamber and adapted to cut off the space between the disks, said disks having central openings and inclined upwardly projecting flanges around said openings, the lowermost disks closest together, and the disks above spaced from those below 90 in relative ratio, the smallest spaces being between the lower disks and the largest spaces between the upper disks, a liquid supply pipe communicating with the center of the lowermost disk, and a needle valve carried by the piston and controlling the outlet from said liquid supply pipe, substantially as described. 95

11. A carbureter comprising a cylindrical 100 casing, a concentric cylinder in the casing forming an annular chamber between the cylinder and the wall of the casing, a plurality of disks below the cylinder spaced apart and communicating with the casing, 105 said casing having an air inlet, a piston fitting the annular chamber and adapted to cut off the space between the disks, said disks having central openings and inclined upwardly projecting flanges around said openings, the opening in the lowest disk being smallest and in the upper disk largest, and the openings in the disks between the upper 110 and the lower disks varying in size in regular ratio, a liquid supply pipe communicating with the center of the lowermost disk, and a needle valve carried by the piston and controlling the outlet from said liquid supply pipe, substantially as described. 115

12. A carbureter comprising a cylindrical 120 casing, a concentric cylinder in the casing forming an annular chamber between the cylinder and the wall of the casing, a plurality of disks below the cylinder spaced apart and communicating with the casing, 125 said casing having an air inlet, a piston fitting the annular chamber and adapted to cut off the space between the disks, said disks

having central openings and inclined upwardly projecting flanges around said openings, the lowermost disks closest together, and the disks above spaced from those below 5 by increasing amounts, the smallest spaces being between the lower disks and the largest spaces between the upper disks, the opening in the lowest disk being smallest and in the upper disk largest, and the openings in the 10 disks between the upper and the lower disks varying in size in regular ratio; a liquid supply pipe communicating with the center of the lowermost disk, and a needle valve carried by the piston and controlling the 15 outlet from said liquid supply pipe, substantially as described.

13. A carbureter comprising a cylindrical casing, a concentric cylinder in the casing forming an annular chamber between the 20 cylinder and the wall of the casing, a plurality of disks below the cylinder spaced apart and communicating with the casing, said casing having an air inlet, a piston fitting the annular chamber and adapted to cut 25 off the space between the disks, a liquid supply pipe communicating with the center of the lowermost disk, said cylinder having slots in its opposite walls, a bar projected through said slots and secured to the piston, 30 and a needle valve secured centrally to the bar and controlling the outlet of liquid from the supply pipe, substantially as described.

14. A carbureter comprising a cylindrical casing, a concentric cylinder in the casing 35 forming an annular chamber between the cylinder and the wall of the casing, a plurality of disks below the cylinder spaced apart and communicating with the casing, said casing having an air inlet, a piston 40 fitting the annular chamber and adapted to cut off the space between the disks, said disks having central openings and inclined upwardly projecting flanges around said openings, a liquid supply pipe communicating 45 with the center of the lowermost disk, said cylinder having slots in its opposite walls, a bar projected through said slots and secured to the piston, and a needle valve secured centrally to the bar and controlling 50 the outlet of liquid from the supply pipe, substantially as described.

15. A carbureter comprising a cylindrical casing, a concentric cylinder in the casing forming an annular chamber between the 55 cylinder and the wall of the casing, a plurality of disks below the cylinder spaced apart and communicating with the casing, said casing having an air inlet, a piston fitting the annular chamber and adapted to 60 cut off the space between the disks, said disks having central openings and inclined upwardly projecting flanges around said openings, the lowermost disks closest together, and the disks above spaced from 65 those below by increasing amounts, the

smallest spaces being between the lower disks and the largest spaces between the upper disks, a liquid supply pipe communicating with the center of the lowermost disk, said cylinder having slots in its opposite walls, a bar projected through said slots and secured to the piston, and a needle valve secured centrally to the bar and controlling the outlet of liquid from the supply pipe, substantially as described.

16. A carbureter comprising a cylindrical casing, a concentric cylinder in the casing forming an annular chamber between the cylinder and the wall of the casing, a plurality of disks below the cylinder spaced 75 apart and communicating with the casing, said casing having an air inlet, a piston fitting the annular chamber and adapted to cut off the space between the disks, said disks having central openings and inclined 80 upwardly projecting flanges around said openings, the opening in the lowest disks being smallest and in the upper disk largest, and the openings in the disks between the upper and the lower disks varying in size 85 in regular ratio, a liquid supply pipe communicating with the center of the lowermost disk, said cylinder having slots in its opposite walls, a bar projected through said slots and secured to the piston, and a needle valve 90 secured centrally to the bar and controlling the outlet of liquid from the supply pipe, substantially as described.

17. A carbureter comprising a cylindrical casing, a concentric cylinder in the casing 100 forming an annular chamber between the cylinder and the wall of the casing, a plurality of disks below the cylinder spaced apart and communicating with the casing, said casing having an air inlet, a piston fitting the annular chamber and adapted to 105 cut off the space between the disks, said disks having central openings and inclined upwardly projecting flanges around said openings, the lowermost disks closest together, and the disks above spaced from 110 those below by increasing amounts, the smallest spaces being between the lower disks and the largest spaces between the upper disks, the opening in the lowest disk being smallest and in the upper disk largest, and the openings in the disks between the upper and the lower disks varying in size 115 in regular ratio, a liquid supply pipe communicating with the center of the lowermost disk, said cylinder having slots in its opposite walls, a bar projected through said slots and secured to the piston, and a needle valve secured centrally to the bar and controlling the outlet of liquid from the supply pipe, 120 substantially as described.

18. A carbureter comprising a cylindrical casing, a concentric cylinder in the casing forming an annular chamber between the cylinder and the wall of the casing, 125

plurality of disks below the cylinder spaced apart and communicating with the casing, said casing having an air inlet, a piston fitting the annular chamber and adapted to 5 cut off the space between the disks, a circular boss on the bottom of said casing below the disks of the same diameter as the disks and the cylinder, and against which said piston is adapted to bear to cut off the flow of air to the disks, substantially as described.

19. A carbureter comprising a cylindrical casing, a concentric cylinder in the casing forming an annular chamber between the 10 cylinder and the wall of the casing, a plurality of disks below the cylinder spaced apart and communicating with the casing, said casing having an air inlet, a piston fitting the annular chamber and adapted to 15 cut off the space between the disks, said disks having central openings and inclined upwardly projecting flanges around said openings, a circular boss on the bottom of said casing below the disks of the same 20 diameter as the disks and the cylinder, and against which said piston is adapted to bear to cut off the flow of air to the disks, substantially as described.

20. A carbureter comprising a cylindrical 25 casing, a concentric cylinder in the casing forming an annular chamber between the cylinder and the wall of the casing, a plurality of disks below the cylinder spaced apart and communicating with the casing, 30 said casing having an air inlet, a piston fitting the annular chamber and adapted to cut off the space between the disks, said disks having central openings and inclined upwardly projecting flanges around said 35 openings, the lowermost disks closest together, and the disks above spaced from those below by increasing amounts, the smallest spaces being between the lower disks and the largest spaces between the upper disks, a 40 circular boss on the bottom of said casing below the disks of the same diameter as the disks and the cylinder, and against which said piston is adapted to bear to cut off the flow of air to the disks, substantially as 45 described.

21. A carbureter comprising a cylindrical 50 casing, a concentric cylinder in the casing forming an annular chamber between the cylinder and the wall of the casing, a plurality of disks below the cylinder spaced 55 apart and communicating with the casing, said casing having an air inlet, a piston fitting the annular chamber and adapted to cut off the space between the disks, said 60 disks having central openings and inclined upwardly projecting flanges around said openings, the opening in the lowest disk being smallest and in the upper disk largest, and the openings in the disks between the 65 upper and the lower disks varying in size

in regular ratio, a circular boss on the bottom of said casing below the disks of the same diameter as the disks and the cylinder, and against which said piston is adapted to bear to cut off the flow of air to the disks, substantially as described.

22. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to 70 cut off the space between the disks, said disks having central openings and inclined upwardly projecting flanges around said openings, the lowermost disks closest together, and the disks above spaced from those below by increasing amounts the 75 smallest spaces being between the lower disks and the largest spaces between the upper disks, the opening in the lowest disk being smallest and in the upper disk largest, and the openings in the disks between the 80 upper and the lower disks varying in size in regular ratio, a circular boss on the bottom of said casing below the disks of the same diameter as the disks and the cylinder, and against which said piston is adapted to 85 bear to cut off the flow of air to the disks, substantially as described.

23. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to 90 cut off the space between the disks, a liquid supply pipe communicating with the center of the lowermost disk, said cylinder having slots in its opposite wall, a bar projected through said slots and secured to the piston, 95 a needle valve secured centrally to the bar and controlling the outlet of liquid from the supply pipe, said supply pipe externally screw-threaded, a nut swiveled in the bottom of said casing and having internal 100 screw-threads engaging the threads of the supply pipe, and means for turning said nut whereby the supply pipe is adjusted toward and away from the valve, substantially 105 as described.

24. A carbureter comprising a cylindrical 110 casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to 115 cut off the space between the disks, said disks having central openings and inclined 120 upwardly projecting flanges around said openings, the opening in the lowest disk being smallest and in the upper disk largest, and the openings in the disks between the 125 upper and the lower disks varying in size

upwardly projecting flanges around said openings, a liquid supply pipe communicating with the center of the lowermost disk, said cylinder having slots in its opposite walls, a bar projected through said slots and secured to the piston, a needle valve secured centrally to the bar and controlling the outlet of liquid from the supply pipe, said supply pipe externally screw-threaded, a nut swiveled in the bottom of said casing and having internal screw-threads engaging the threads of the supply pipe, and means for turning said nut whereby the supply pipe is adjusted toward and away from the valve, substantially as described.

25. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to cut off the space between the disks, said disks having central openings and inclined upwardly projecting flanges around said openings, the lowermost disks closest together, and the disks above spaced from those below by increasing amounts, the smallest spaces being between the lower disks and the largest spaces between the upper disks, a liquid supply pipe communicating with the center of the lowermost disk, said cylinder having slots in its opposite walls, a bar projected through said slots and secured to the piston, a needle valve secured centrally to the bar and controlling the outlet of liquid from the supply pipe, said supply pipe externally screw-threaded, a nut swiveled in the bottom of said casing and having internal screw-threads engaging the threads of the supply pipe, and means for turning said nut whereby the supply pipe is adjusted toward and away from the valve, substantially as described.

26. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to cut off the space between the disks, said disks having central openings and inclined upwardly projecting flanges around said openings, the opening in the lowest disks being smallest and in the upper disk largest, and the

openings in the disks between the upper and the lower disks varying in size in regular ratio, a liquid supply pipe communicating with the center of the lowermost disk, said cylinder having slots in its opposite walls, a bar projected through said slots and secured to the piston, a needle valve secured centrally to the bar and controlling the outlet of liquid from the supply pipe, said supply pipe externally screw-threaded, a nut swiveled in the bottom of said casing and having internal screw-threads engaging the threads of the supply pipe, and means for turning said nut whereby the supply pipe is adjusted toward and away from the valve, substantially as described.

27. A carbureter comprising a cylindrical casing, a concentric cylinder in the casing forming an annular chamber between the cylinder and the wall of the casing, a plurality of disks below the cylinder spaced apart and communicating with the casing, said casing having an air inlet, a piston fitting the annular chamber and adapted to cut off the space between the disks, said disks having central openings and inclined upwardly projecting flanges around said openings, the lowermost disks closest together, and the disks above spaced from those below in relative ratio, the smallest spaces being between the lower disks and the largest spaces between the upper disks, the opening in the lowest disk being smallest and in the upper disk largest, and the openings in the disks between the upper and the lower disks varying in size in regular ratio, a liquid supply pipe communicating with the center of the lowermost disk, said cylinder having slots in its opposite walls, a bar projected through said slots and secured to the piston, a needle valve secured centrally to the bar and controlling the outlet of liquid from the supply pipe, said supply pipe externally screw-threaded, a nut swiveled in the bottom of said casing and having internal screw-threads engaging the threads of the supply pipe, and means for turning said nut, whereby the supply pipe is adjusted toward and away from the valve, substantially as described.

In testimony whereof I have signed my name to this specification in the presence of two subscribing witnesses.
